TELEGRAPHIC TRANSMITTER

Lynn G. Heatherly, Whiteville, N. C.

Application September 13, 1941, Serial No. 410,735

1 Claim. (Cl. 178—82)

This invention relates to a telegraphic transmitter which may be employed for sending messages in code, either by a telegraph circuit or wireless and of the character having a key, a vibrator and electrical connections.

The primary object of this invention is to provide a construction which will be efficient from every standpoint and which will be durable, compact and rigid, with the danger of any of the parts becoming disconnected or disarranged entirely eliminated, and to remain free of corruptions, rust or the like, regardless of what kind of damaging conditions it may be subjected to and also will have such weight as to assure against creeping on its support during the use thereof.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a top plan view partly in section illustrating a telegraphic transmitter constructed in accordance with my invention.

Figure 2 is a bottom plan view illustrating the device.

Figure 3 is a side elevation partly in section illustrating the device.

Figure 4 is a transverse sectional view taken on the line 4—4 of Figure 1.

Figure 5 is a transverse sectional view taken on the line 5—5 of Figure 1.

Referring in detail to the drawings, the numeral 5 indicates a flat elongated electric conductive base provided with cushioned insulating feet 6 on its under face and detachably secured thereto by screws or like fasteners. It is preferable to employ three supporting feet, a pair of which is located adjacent one end of the base and the other or single foot is located adjacent the other end of said base.

Pairs of rigid and vertically arranged posts 8 and 9 extend upwardly from the top face of the base. The pair of posts 8 is spaced a limited distance from one end of the base while the pair of posts 9 is located adjacent the other end of the base.

Insulating strips 10 are arranged between the lower ends of the posts and the top face of the base. A rigid electric conductive strip 11 is arranged between the top face of the base and the

conductive strip 10 positioned under the lower ends of the pair of posts 8 and acts as a bearing for one end of a pivot 12 so that said pivot will have an effective electrical connection with the base. This pivot is employed for supporting longitudinally of the base a key 13 including a vibrator 14.

The upper ends of the posts 9 are rigidly connected by a transverse metallic strip 15 detachably secured to the upper ends of said posts 9 by screws or like fasteners 16. The upper ends of the posts 8 are rigidly connected together by a rigid strip 17 insulated from the upper end of said posts 8 by an insulating strip 18. Screws or like fasteners 19 detachably secure to the posts 8 the strips 17 and 18.

The posts 8 and 9 have integral therewith rigid electric conductive members or bars 20 paralleling each other. Screws 22 secure on the bars 20 rigid metallic strips 24 which parallel said bars for a limited distance and are further secured to the latter by screws or fasteners 25, the latter being insulated from said metallic strips 24 by insulating collars 26. The strips 24 are insulated throughout their length from the bars 20 by insulating strips 27. The posts 9 are detachably secured to the base by stud bolts 28 insulated from said base by insulating sleeves or collars 29. The posts 8 are detachably secured to the base 5 by stud bolts 30 insulated from said base by insulating collars or sleeves 31.

The base 5, bars 20, posts 8 and 9 and the means of connecting said parts go to provide an extremely rigid and durable construction.

35 The key 13 is of sectional formation including the rigid members 32 and 33. The pivot 12 extends through and is fixed to the member 32 of the key while the member 33 has formed on one end a U clamp 34 which straddles the member 32 and is journaled on the pivot 12, which construction will permit the member 33 to have a pivotal movement with respect to the member 32 when moved in one direction and will move the member 32 therewith when moved in an opposite direction. The ends of the pivot pin are pointed, the upper end fitting in a socket of an adjusting post 35 threaded in the member 17 and held against accidental rotation by a lock nut 36 which turns tightly against the rigid member 17.

The lower pointed end of the pivot pin fits in a socket of an adjusting post 37 threaded in the base 5 and is provided with a screw driver kerf in its lower end. Said lower end of the adjust-

ing post is located within a recess 38 provided in the base.

A screw 39 is carried by the member 33 of the key 13 and extends loosely through an opening 40 provided in the member 32 and has threaded thereon a nut 41 engaged by one end of a coil spring 42, the other end of which bears against the member 32. It is understood that the coil spring 42 surrounds the bolt and acts to urge the member 33 against the member 32. The free end of the member 33 is equipped with finger pieces 42' located beyond one end of the base so that they may be gripped between the thumb and forefinger of the hand of an operator. The screw 39 also secures to the member 33 a contact 43 arranged opposite a contact 44 carried by an adjusting screw or post 45 threaded in one of the bars or members 20 and held against accidental movement with relation thereto by a nut 46 threaded tightly against the latter-named bar or member.

Opposed and spaced adjustable stops 47 in the form of screws extend through the bars or members 20, insulating strips 27 and metallic strips 24 and are threaded in the latter so that they may be adjusted toward and from each other. The insulating strips 27 include insulating collars 48 which insulate the stops 47 from the bars 20. Lock nuts 49 are threaded on the stops and against the strips 24 to prevent the stops from moving out of adjustment.

The member 32 of the key 13 extends between the opposing ends of the stops 47 and is normally urged into engagement with the right hand stop by the action of an expansion type coil spring 50, which has one end fastened to the member 32 and the opposite end attached to an adjusting screw 51 which extends through one of the members 20, one of the insulating strips 27 and is threaded in one of the metallic strips 24. The adjusting screw 51 is equipped with a lock nut 52 whereby it may be firmly held in any of its adjusted positions. The adjusting screw 51 permits the tension of the spring 50 to be varied.

The vibrator 14 which includes a rod 52, a pair of weights 53, and a stop collar 54 is flexibly secured to the free end of the member 32 of the key 13 by a leaf spring 55. The spring 50 acting on the key 13 normally positions the rod 52 of the vibrator 14 against a stop 56 in the form of a disc journaled on an insulated bracket 57 secured on one of the posts 9 by a screw 21. The weights 53 may be adjusted longitudinally of the bar 52 for varying the action of the vibrator 14 and secured in any of their adjusted positions by set screws 58.

The collar 54 acts as a stop for the adjustment of the weights on the bar or rod 52 in one direction and also as an attaching medium for a substantially U-shaped contact spring 59 to the bar of the vibrator. One end of the spring 59 is attached to the stop collar 54 and the opposite end carries a contact 60 coactive with a contact 61 carried by an adjusting screw 62 threaded in one of the bars or members 20 and is equipped with a lock nut 63. When the key is at rest and the vibrator or the bar 52 thereof is in engagement with the stop 56, the contacts 60 and 61 are spaced. This also applies to the contacts 43 and 44 and further it will be noted that the member 32 of the key at this time is in engagement with the right hand stop 47. The key is caused to assume this position normally by the action of the spring 50.

When this instrument is connected into a telegraph circuit or associated with a wireless apparatus the contacts 60 and 61 due to the action of the vibrator 14 are employed for sending dots 5 while the contacts 44 and 43 are employed for making dashes.

When the key 13 is swung on its pivot to engage with the left hand post and then released causes the vibrator 14 to oscillate or vibrate 10 backward and forward several times for the purpose of engaging and disengaging the contacts 60 and 61 to make the dots in the code. It is to be understood that the vibration of the vibrator continues for a considerable length of 15 time and as long as the key is moved to engage the left hand stop 47 the instrument will continue to send the dots in the telegraph line. However, when the finger pieces 42 are released and the key assumes a position engaging the 20 right hand stop under the action of the spring 50 and the contacts 60 and 61 will be spaced a sufficient distance apart that they will not engage during a vibratory movement of the vibrator 14. Also it will be noted that as soon as the key assumes the latter-named or neutral position, the vibrator bar 52 comes into engagement 25 with the stop 56 and thereby arrests the vibration of the vibrator.

To send the dashes by the instrument, the finger pieces 52 are moved to the left back and forth by the operator engaging and disengaging the contacts 43 and 44, the member 32 of the key remaining in its neutral position by the action of the spring 50 and the movement permitted between the members 32 and 33 by the spring 42.

The electric lead of the telegraph circuit is indicated by the character 70 and enters a socket 71 provided in the base and the conductor 72 thereof is electrically secured to the base, as 30 shown at 73, while the conductor 74 of the lead is connected to one of the screws or fasteners 28 and thereby becomes electrically connected to the parallel bars or members 20 so that a circuit may be made and broken through the operation 35 of the key 13, it being noted that the circuit is completed when either groups of contacts are engaging with each other through the manual operation of the key and through the fact that the pivot of the key is electrically connected to 40 the base by the bearing pin 37. Whenever it is desired to render the key 13 inoperative or ineffective as to making and breaking of the telegraphic electric circuit, a switch 75 is provided and is mounted on the base adjacent to the finger 45 pieces 42' of the key so that the operator can easily and conveniently actuate the switch by the hand employed for the actuation of the key. The switch is electrically grounded to the base and includes a condenser 76 electrically connected thereto and mounted within a recess 77 provided in the base. The condenser 76 is electrically connected to one of the screws 30 by a conductor 78 which electrically connects the condenser to the parallel bars and completes the telegraphic 50 circuit when the switch is closed by connecting the base thereto.

It is to be understood that when the switch 55 is in a closed position the telegraphic circuit is completed and the key 13 is electrically cut out therefrom or will not have any action in making and breaking said circuit if said key should be 60 manually operated. However, when the switch is opened then the key 13 becomes effective in making and breaking of the telegraphic circuit for 65

the purpose of sending the dots and dashes as heretofore explained.

The lead 70 is equipped with an anchoring cord 80 secured to the base 5 by being passed through an opening 81 in the base and suitably tied to itself.

It is to be understood that all of the metallic parts of this instrument are heavily chromium plated and such parts made from brass so as to resist to the maximum, corroding, rusting or the like so as to render the instrument extremely serviceable under the most severe adverse conditions. Also it is to be understood that the contacts employed in the instrument are to be made from virgin silver and the springs of the finest grade of steel, all of which will add to the serviceability and life of the instrument. Furthermore, it will be apparent that an instrument of the construction described in detail and shown in the drawings will be extremely rigid and that all the parts which are separable will be prevented from accidental displacement. This durable construction besides possessing the qualities and advantages as specified, defines a construction of considerable weight so that when the instrument is placed upon a desk or the like support it will not creep or move about when in use.

While I have shown and described the preferred embodiment of my invention, it will be un-

derstood that minor changes in construction, combination and arrangement of parts may be made without departing from the spirit and scope of the invention claimed.

Having thus described the invention, what I claim is:

In a telegraphic transmitter, the combination of a two-part key movable as a unit in one direction, part of the key being movable independently in the other direction, a stop to limit the movement of the key as a unit, a spring supported vibrator carried by the key whereby the vibrator will be kept from vibrating when the key strikes said stop, a pair of contacts constituting the terminal of an electric circuit, one of said contacts being carried by the vibrator and the other being located in the path of the first, means actuated by the independently movable part of the key for making and breaking the circuit independently of the vibrator, a rigid supporting frame having the key pivotally and adjustably mounted thereto and including rigid spaced parallel side members and pairs of rigid supporting posts detachably connected, rigid means tying the posts in pairs and detachable therefrom, and a weighted base for the support of said posts and detachably secured thereto.

LYNN G. HEATHERLY.
